SHIRT COLLAR

Paul W. Napierala, Reedpoint, Mont.

Application November 18, 1939, Serial No. 305,181

2 Claims. (Cl. 2—131)

My invention relates to improvements in detachable collars for shirts and has for its primary object to provide a collar which eliminates the necessity for the conventional rear collar button so that the collar will be more comfortable to wear, the nature of the invention being such that the collar will remain snugly in place at all times and will not tend to "climb" up the wearer's neck.

Additionally, the invention contemplates a detachable collar having an extension that may be faced with material that will be softer or possess greater anti-frictional qualities than the material of which the collar is made—or of which the neck-band of the shirt is made.

More specifically stated, it is an object of the invention to provide a collar having a neckband portion the lower edge of which is provided with an extension portion and which portion is adapted to extend under the neckband of the shirt and overlie the neck of the wearer so that when the shirt collar is buttoned it will engage the extension portion of the collar neckband to retain the collar in place in the back thereof; and said neckband portion of the collar may have a facing of softer material than that of which the collar is made.

The invention aims also to provide a detachable collar for shirts which is inexpensive in construction, easy to apply, and comfortable to wear.

In the drawing which illustrates the now preferred form of the invention,

Figure 1 is a perspective view illustrating my detachable collar in place in association with a 35 detachable collar shirt.

Figure 2 is a plan view of my collar spread open and showing the novel extension of the neckband of the collar;

Figure 3 is a fragmentary cross sectional view 40 through the collar applied to a shirt.

Referring to the drawing by reference characters, my detachable collar is shown at 4 having a neckband portion 5' provided with tabs 6 and buttonholes 6' at each end. The lower edge of the neckband 5' is provided with a depending flap or extension 5'. In the present instance the collar is of the turn-down variety and has the usual turn-downed flap or portion 7, as indicated, which folds downwardly into 50 position as shown in Figure 1 along the fold-line 8 of Figure 2.

As illustrated, the neckband extension 5 of the collar is approximately two times wider than the front turn-downed portion 7. This rear por-

tion 5 fits inside of the shirt 9 around the lower neck and thus eliminates the use of rear collar buttons. If desired this part may be faced with silk or satin to keep the neck warm in cold 5 weather and serves similar to a muffler or scarf.

It will be evident that when the neckband 10 of the shirt 9 is buttoned and the collar button 11 secured in the button holes 6 of the detachable collar the extension 5 of the collar, since it fits inside of the shirt as clearly shown in Figure 3, is prevented from escaping by the action of the buttoned shirt neckband 10 which serves to grip or hold the extension in place. In this way the necessity for a rear collar button is obviated.

15 It is to be noted, also, that when the flap 7 of the collar is turned down over the neckband 10 of the shirt and collar buttoned that the shirt neckband 10 will be gripped between the free edge and adjacent area of the flap 7 and the lower part of the collar neckband 5' whereby to assist the flap 5 to hold the collar in place. At the same time, it should be noted that a closed space is provided between the flap 7 and collar neckband 5' which may partially receive a necktie (not shown) therebetween above the upper free edge of the shirt neckband 10 (Fig. 3). Thus, the upper edge of the shirt neckband 10 which closes this space at the bottom and the adjacent inner surface of flap 7, grip the tie therebetween and prevent the necktie from dropping down and maintain it properly positioned in the collar.

From the foregoing description taken in connection with the accompanying drawing, it will be apparent that I have provided a very convenient and comfortable detachable collar which eliminates the discomfort incident to the use of a collar button, yet which will remain snugly and properly in place by the buttoning of the neckband of the shirt and the securing of the neckband buttonholes 6 of the collar to the front collar button 11.

This detachable collar serves to keep the neckband of the shirt clean and also serves to prevent the neckband of the shirt from ridging or scraping the neck of the wearer.

Thus it is seen that this collar differs materially from the conventional one. In the conventional collar the band portion fits around the outside of shirt neck-band where it is held thereon by front and rear collar buttons. In the improvement herein described the neck-band of the collar does not fit on the outside of the neck-band but around the inside thereof, it being of sufficient width to be held by the buttoned neck-band

of the shirt and consequently no rear buttons are required. The tabs 6 are, of course, fastened inside of the shirt band to the button 11. In laundering, the extension 5 of the collar is left unstarched to provide a softer surface around the neck.

While I have illustrated the invention in its now preferred form, yet it will be obvious that many changes or modifications may be made in same without departing from the spirit and scope of the subject matter claimed hereinafter.

Having thus described my invention what I claim as new is:

1. A detachable collar for shirts having an up-standing neckband, said collar having a neckband substantially wider than that of the shirt, a downwardly turned flap carried by the upper

edge of said collar neckband, the lower edge of said flap being adapted to overlie the outer surface of said shirt neckband, the lower edge portion of said collar neckband being adapted to overlie the inner surface of said shirt neckband, a space between the opposed surfaces of said flap and collar neckband above the upper edge of said shirt neckband, and means for forcing said lower edge portions of said collar neckband and flap into gripping engagement with said shirt neckband.

2. The structure of claim 1, a depending flap formed on the lower edge of said collar neckband and adapted to underlie the lower edge of said shirt neckband.

PAUL W. NAPIERALA.
